PERFORATING AND CLOSING DEVICE

Phillip Monnett, Toledo, Ohio, assignor to Meco, Inc., Napoleon, Ohio, a corporation of Ohio

Application June 15, 1948, Serial No. 33,117

1 Claim. (Cl. 220—51)

1

This invention relates to devices for perforating the tops of containers for liquids such as condensed milk and fruit juices which usually are packaged in cans and often are poured from the cans as used, the unused portions being left in the cans for storage.

When a can of condensed milk, for example, is opened it is customary to puncture two holes in the top. One of the holes is punctured adjacent the rim to act as a pouring spout and another hole is punctured at approximately the opposite side of the top to act as an air vent. These holes often are made with tools such as ice picks or can openers or the points of heavy knives, none of which are designed for the job.

When a can of condensed milk is left, even under refrigerated conditions, with a pair of holes so perforated in its top, the small residue of milk which clings to the edges of the pouring hole or spills over onto the top of the can often sours or further evaporates so that a yellowish, fatty residue is left on the can around the pouring opening. This residue is unappetizing in appearance and is unsanitary and it may often, in fact, form across the pouring hole, plugging it.

The principal object of this invention is to provide a small neat device through the use of which two neatly placed, sufficiently sizable orifices can be punctured in the top of a liquid containing can with one simple motion and which device can then be reinserted into the hole so perforated to serve as a closure, thus to prevent air from reaching the contents of the can or those portions of the substance which cling to the inner edges of the pouring orifice.

It is another object of this invention to provide a perforating and closing device for liquid containing cans which is inexpensive and simple to manufacture, easy to use and neat in appearance.

It is another object of this invention to provide a device for closing the holes which were perforated with the device in order to permit liquid to be poured from the can, which is so designed that air is permitted to reach the top surface of the can surrounding the holes thereby to dry up any residue but is prevented from entering the can by virtue of the fact that the holes are sealed.

In the drawings:

Figure I is a view in perspective of a perforating and closing device embodying the invention.

Figure II is a bottom view of the device shown in Figure I.

Figure III is an isometric view of a can of the type in which condensed milk or other liquids are packaged showing the location of the two holes

2

perforated through the use of a device embodying the instant invention.

Figure IV is a vertical sectional view of the can shown in Figure III and illustrating how a device embodying the invention is replaced to close the perforations formed in the top of the can by the device itself.

A device embodying the invention comprises a unitary body 1 which preferably is molded in a single molding from a plastic material such as, for example, urea-formaldehyde or melamine-formaldehyde which are non-toxic and practically impervious to food acids. The body 1 has a centrally located ear-like handle 2 by means of which the device is grasped in the fingers and a pair of longitudinally extending arms 3 as well as a pair of laterally extending balancing arms 4. In the underside of each of the arms 3 there is a vertical bore into which is forced a short sharp piercing point or punch 5. It is the punches 5 which perforate the holes in the lid of a can to be opened and which also serve to seal the holes after they have been perforated. The upper ends of the punches 5, as seen in Figure IV, may be serrated or roughened so that when they are molded or inserted in the ends of the arms 3 the serrations or rugations tend to restrict the punches 5 against either rotary or longitudinal movement in the body 1.

The interior of the handle portion 2 may be hollow, as shown in Figure II, in order to save weight and material, or it may be made solid. While it has been found that a device embodying this invention can be most economically and efficiently constructed from a plastic material, it must be remembered that plastics are but substitutes for natural materials and a device identical with that shown in the drawings easily could be made from metal, wood or other substance.

In Figure III there is shown a can 6 which has a flat disc-like top 7 sealed to a sheet of metal forming a cylindrical body 8 of the can. The top 7 is sealed to the body 8 by means of an annular rim 9, the two pieces of metal being crimped together. Because the edges of the disc 7 and cylinder 8 must be overlapped in order to crimp together, the rim 9 is raised some little distance above the horizontal level of the top 7. In Figure III there can be seen two perforations 10 and 11 either of which may be used as a pouring spout, the other serving as an air vent.

In Figure IV a device embodying the invention is shown in position on a can sealing the apertures formed in the top of the can. In Figure IV it can

be seen that the punches 5 fit back into the apertures 10 and 11 which originally were formed as the punches were forced through the lid 7 of the can. On the underside of each of the lateral arms 4 there is formed a button 12 which extends beneath the lower surface of the body 1 a distance approximately equal to the vertical thickness of the rim 9. The two buttons 12 act as lateral supports for the body 1 so that when the punches 5 are reinserted in the holes formed in the lid 7 the device does not have a tendency to rock back and forth and work its way off the top of the can but remains stable and lies flat on the can.

The simplicity of the device, consisting, as it does, of merely a unitary body and two perforating punches, results in an extremely low manufacturing cost. It also facilitates the high speed production of the devices so that they can be sold but for a few cents. The design and organization of the parts of the device from which the advantages in manufacture and use accrue are set forth in the subjoined claim.

Having described the invention, I claim:

A combined perforating and closing device for condensed milk cans comprising a web-like body molded of a non-toxic resin and having two longitudinally extending arms and shorter laterally extending arms, all of said arms having a

substantially planar lower surface free of dirt retaining crevices, a perforating punch mounted in the lower side of each of said longitudinally extending arms and extending downwardly therefrom, said body having a maximum dimension through said longitudinally extending arms slightly greater than the diameter of the top of a commonly used condensed milk can and a dimension through said laterally extending arms less than such diameter, a centrally located, upwardly extending, manually graspable handle portion on said body, and downwardly extending protuberances on the undersides of said laterally extending arms, said protuberances being of a length substantially equal to the height of the rims formed on such cans.
